UNITED STATES PATENT OFFICE.

AUGUST KIRCHHOFER, OF NASHVILLE, TENNESSEE, ASSIGNOR OF ONE-HALF TO
THOMAS A. CLARKSON, OF NASHVILLE, TENNESSEE.

AUTOMATIC SIGHT-FEED GRAPHITE LUBRICATOR.

1,145,318.

Specification of Letters Patent.

Patented July 6, 1915.

Application filed June 1, 1914. Serial No. 842,184.

To all whom it may concern:

Be it known that I, AUGUST KIRCHHOFER, a citizen of the United States, residing at Nashville, in the county of Davidson and State of Tennessee, have invented a new and useful Automatic Sight-Feed Graphite Lubricator, of which the following is a specification.

The invention relates to improvements in graphite lubricators.

The object of the present invention is to improve the construction of graphite lubricators and to provide a simple, practical, and efficient graphite lubricator, of compact and inexpensive construction, designed for use on modern high speed locomotives and various other types of steam engines, as well as internal combustion engines, and capable of automatically operating in unison with the engine through fluid pressure and adapted to be readily adjusted to control the feed of the graphite.

A further object of the invention is to provide a graphite lubricator adapted to automatically vary the feeding of the lubricant with the speed of an engine, so that when a locomotive or other engine is operating at high speed, it will receive a maximum amount of lubrication, and a less quantity of the lubricant will be fed to the same when the engine is traveling at a lower speed.

With these and other objects in view the invention consists in the construction and novel combination of parts hereinafter fully described, illustrated in the accompanying drawings, and pointed out in the claims hereto appended, it being understood that various changes in the form, proportion, size and minor details of construction, within the scope of the claims, may be resorted to without departing from the spirit or sacrificing any of the advantages of the invention.

In the drawings: Figure 1 is an end elevation of a graphite lubricator constructed in accordance with this invention. Fig. 2 is a central vertical longitudinal sectional view of the same. Fig. 3 is a central transverse sectional view of the graphite lubricator. Fig. 4 is a central longitudinal sectional view of a graphite lubricator showing another form of the invention.

Like numerals of reference designate cor-

responding parts in all the figures of the drawings.

In the drawings, in which is illustrated the preferred embodiment of the invention, the graphite lubricator comprises in its construction a cylinder 1 preferably consisting of a casting and provided with a central vertical integral magazine 2 for the reception of graphite 3. The graphite 3 is preferably in the form of cylinders, and the latter are arranged in a vertical position within the magazine, which is of circular or cylindrical shape. The lubricant fits loosely within the cylindrical magazine, which is exteriorly threaded at its upper end 4 for the reception of a removable cap 5. The cap 5, which forms an extension of the magazine or receptacle, is interiorly threaded at its lower end at 6 to engage the threads of the magazine 2 and it is also provided above the threaded portion 6 with a shoulder 7 between which and the upper end of the magazine is interposed a gasket 8. The gasket 8, which is adapted to provide a steam tight joint between the cap and the magazine, also serves as a guide for a weight 9, which is adapted to feed the graphite downwardly as the same is consumed. The shoulder 7 of the cap 5 is spaced from the threaded portion 6, a groove 10 being preferably formed between the shoulder and the threaded portion. The gasket 8 extends into the cap beyond the inner walls of the magazine and is provided with an opening of a size to guide and center the weight, and it has perforations 11 at an intermediate point between the weight and the walls of the cap to admit fluid pressure above the gasket. The weight, which rests upon the stack or pile of graphite blocks or cylinders, is preferably of cylindrical form and has an enlarged half-round head 12 at its upper end. The cap, which is of substantially cylindrical form, is preferably provided with a rounded top and its lower end, which is enlarged, has a polygonal wrench receiving exterior to enable it to be readily screwed on and off the threaded upper end of the magazine.

The cylinder 1, which is horizontally disposed, receives opposite piston heads 13 secured to the terminal portions of a piston rod 14, which is provided with an intermediate threaded portion 15 against which the

graphite is pressed by the action of the weight 9. The threads scrape the graphite and cause the same to be dropped into the lower portion of the cylinder in fine powdered form, but instead of threading the central graphite engaging portion of the piston rod, the latter may be provided with any other suitable means for removing finely divided lubricating particles from the solid cylinders or blocks of graphite. The piston heads 13, which may be of any preferred construction, are secured to the ends of the piston rod in any suitable manner. The ends of the horizontal cylinder 1 are provided with interior screw threads 16 into which are screwed the cylinder heads or ends 17, having reduced threaded portions 18 which engage the interior threads of the cylinder 1. The reduction of the inner threaded portions 18 of the heads or ends 17 of the cylinder forms annular shoulders 19, which engage the end edges or faces of the cylinder 1. The cylinder heads or ends are provided with central threaded bores or openings 20 for the reception of screws 21 adapted to project interiorly of the cylinder 1 for limiting the stroke of the piston heads and the consequent feeding of the graphite by the lubricator. The ends or heads 17 are provided at the outer ends of the bores or openings 20 with exterior enlargements 22 and have central recesses 23 at the inner ends of the said bores or openings. The heads 24 of screws which secure the piston heads 13 to the ends of the piston rod 14 are adapted to extend into the central recesses 23 and engage with the inner ends of the adjusting screws 21 when the latter are adjusted to a projecting position. The adjusting screws 21 are equipped with jam or lock nuts 25, which engage the exterior enlargements and secure the screws 21 in their adjustment.

The cylinder is provided with a central depending exteriorly threaded nipple 26 which is designed to be screwed into a threaded opening of the steam chest of a locomotive or other engine for feeding the graphite lubricant to the same. The cylinder is also provided adjacent to its ends with interiorly threaded flanges 27 surrounding port openings 28 and adapted to be connected by suitable pipe connections with the end portions of the steam cylinder of an engine (not shown), so that when steam is admitted to one end of such steam cylinder, it will also be admitted to the corresponding end of the cylinder 1 and will operate to move the piston rod and the piston heads toward the other end of the cylinder 1. When the steam is fed to the other end of the engine cylinder, it will be simultaneously admitted to the corresponding end of the cylinder 1 and will operate to reciprocate the piston 14, which, by being actuated by the fluid

pressure of an engine, automatically operates in unison with the engine feeding a maximum amount of the graphite lubricant when the engine is traveling at its highest speed, and a less amount of lubricant when the engine is traveling at a lower speed. Steam of the same pressure as obtains in the steam chest is admitted to the central portion of the cylinder 1 and to the magazine, and pressure acting against the inner face of one of the piston heads 13 counterbalances that acting against the inner face of the other piston head, so that the steam pressure admitted to the central portion of the cylinder 1 and the magazine does not affect the operation of the graphite feeding means. The cylinder 1 is provided below the opposite walls of the magazine with vertical webs 29 having perforations 30 dividing the cylinder 1 into end piston head receiving chamber and a central lubricant space or compartment. The webs 29 are also provided with aligned central openings 31, through which the horizontal piston rod 14 passes. The central portion of the cylinder is beveled or flared at 32 for directing the falling lubricant into the nipple.

The lubricator is provided at opposite sides with sight openings formed by laterally extending horizontally disposed tubular portions 33, located at the top of and formed integral with the cylinder 1. The openings of the tubular projecting portions 33 are located above the plane of the compartments of the cylinder 1 and are arranged in alignment, as clearly illustrated in Fig. 3 of the drawings. Glasses 34, consisting of plates or disks, are secured over the ends of the tubular portions 33 by caps 35 having apertures 36 registering with the openings of the said tubular portions 33. The caps 35 are interiorly threaded at 37 to engage exterior threads 38 of the tubular portions 33. The sight openings expose the graphite and enable the feed or consumption of the same to be readily seen. The opposite sight openings are of less diameter than the cylinders of graphite, so that there is no liability of the graphite accidentally becoming lodged in the sight openings, which will not interfere with the proper feeding of the graphite to the piston rod 14.

In Fig. 4 of the drawings is illustrated another form of the invention, in which the cylinder is provided with end portions 39 and 40, receiving differential piston heads 41 and 42 connected by a piston rod having a centrally threaded portion for scraping the graphite. The cylinder is provided with a central exteriorly threaded nipple 43 to screw into the steam chest, and it is provided at one end with a port opening 44 surrounded by a depending interiorly threaded annular flange 45, adapted to receive pipe connections for connecting the

outer end 39 of the cylinder with one end of the steam cylinder of a locomotive. The smaller end 40 of the cylinder of the lubricator is provided with a port opening 5 or vent 46 communicating with the outside atmosphere to prevent any back pressure from interfering with the outward movement of the smaller piston head 42. The inner faces of the differential piston heads are subject to constant pressure, and the pressure on the surface of the larger piston head 41 will operate to force the piston in the direction of the end of the cylinder having the port opening 44 when the steam is exhausted at that point. When, however, steam is admitted to this end of the cylinder, the pressure on the outer end of the larger piston head 41 will operate to move the same inwardly and reciprocate the piston rod toward the outer end of the smaller portion 40 of the cylinder of the lubricator. In this manner the lubricator having the differential piston heads is automatically operated by fluid pressure, and in unison with the engine with which it is connected. When the lubricator is applied to an internal combustion engine, it is connected with the pipe between the carbureter and the cylinders.

30 The tendency at the present period among railroads generally, and other users of steam, is toward higher pressure, and often superheated steam and the use of oil as a lubricant is not entirely satisfactory in all cases.

35 Flaked graphite has long been known as a superior lubricant, having the peculiar quality of being adapted to be forced into the superficies of cylinders and valves of steam engines and pumps, due to the motion of the moving parts, imparting or giving off a highly finished surface, thus reducing the friction and lessening the consumption of oil. While graphite possesses high lubricating qualities, it is not advisable to use it alone, and it is deemed to be a good practice to use in connection with a graphite lubricator either an oil pump or a sight feed lubricator, as are now in use. When graphite and oil are employed, it is only necessary to feed about one-third as much oil as when no graphite is used. Another valuable feature of graphite is that it fills up the crevices and interstices of the packings, and with it, stuffing boxes need not be kept so tight, and the friction of the rods and valve stems is lessened and at the same time, the durability of the packing is considerably increased.

What is claimed is:—

60 1. A lubricator of the class described comprising a cylinder, a receptacle adapted to hold a mass of lubricant in the form of a solid, said receptacle having an opening connected with the cylinder, and a piston operating in the cylinder and adapted to be actuated by the fluid pressure of an engine,

said piston having a stem or rod reciprocating at the opening of the receptacle and provided with means for removing from the said solid finely divided lubricating particles.

70 2. A lubricator of the class described comprising a cylinder, a receptacle connected with the cylinder and adapted to hold a mass of lubricant in the form of a solid, spaced piston heads located in the cylinder 75 at opposite sides of the receptacle and adapted to be actuated by the fluid pressure of an engine, and means located between and reciprocated by the piston heads for removing finely divided lubricating particles 80 from the solid mass of lubricant.

3. A lubricator of the class described including a cylinder provided at a point intermediate of its ends with a magazine adapted to hold a mass of lubricant in the 85 form of a solid, and a piston operating within the cylinder and adapted to be actuated by fluid pressure of an engine, said piston having a piston rod provided with a roughened surface arranged to remove 90 finely divided lubricating particles from the solid mass of lubricant.

4. A lubricator of the class described including a cylinder provided at a point intermediate of its ends with a magazine 95 adapted to hold a mass of lubricant in the form of a solid, and a piston operating within the cylinder and including spaced piston heads and a connecting piston rod having means for removing from the solid 100 mass of lubricant finely divided lubricating particles.

5. A lubricator of the class described including a cylinder provided at a point intermediate of its ends with a magazine 105 adapted to hold a mass of lubricant in the form of a solid, and a piston operating within the cylinder and including spaced piston heads and a connecting piston rod having a roughened surface arranged to 110 remove finely divided lubricating particles from the solid mass of lubricant.

6. A lubricator of the class described including a cylinder provided at a point intermediate of its ends with a magazine and having sight openings located at opposite sides thereof, and a piston operating within the cylinder and including spaced piston heads and a connecting piston rod having a roughened surface for removing finely 115 divided particles of lubricant from a solid mass of lubricant contained in the said magazine.

7. A lubricator of the class described including a cylinder provided at a point intermediate of its ends with a magazine for holding a solid mass of lubricant, said cylinder being also provided at its ends with ports or openings, and a piston arranged 125 within the cylinder and adapted to be actuated by the fluid pressure of an engine,

ated by fluid pressure and to operate in unison with an engine, said piston comprising spaced piston heads and a connecting piston rod carrying means for removing finely divided lubricating particles from the solid mass of lubricant.

8. A lubricator of the class described including a cylinder having an outlet designed to be connected with an engine and 10 provided above the same with a magazine adapted to contain a solid mass of lubricant, said cylinder being also provided below the magazine with transverse webs having openings, a piston including piston 15 heads operating within the cylinder beyond the said webs, and a piston rod connecting the piston heads and extending through the webs, said piston rod carrying a roughened surface adapted to remove from the solid 20 mass of lubricant finely divided lubricating particles.

9. A lubricator of the class described including a cylinder provided at a point intermediate of its ends with an outlet designed to be connected with an engine, said cylinder being also provided with end ports, and a piston operating within the cylinder and including spaced piston heads and a connecting piston rod carrying means for removing from a solid mass of lubricant 25 finely divided lubricating particles, said piston being adapted to be actuated by fluid pressure so as to operate in unison with an engine.

In testimony, that I claim the foregoing 35 as my own, I have hereto affixed my signature in the presence of two witnesses.

AUGUST KIRCHHOFER.
